CIGARETTE HOLDER

Filed Oct. 13, 1928

UNITED STATES PATENT OFFICE

MILES F. DEACH, OF OAKLAND, CALIFORNIA

CIGARETTE HOLDER

Application filed October 13, 1928. Serial No. 312,338.

The invention relates to a cigarette holder having a sleeve portion slidably and telescopically receiving a stem portion in effecting the ejection of a cigarette butt from 5 the sleeve.

An object of the invention is to provide a holder of the class described in which the accumulation of deposits in the sleeve portion is positively prevented.

Another object of the invention is to provide a cigarette holder structure in which no leakage of moisture from the sleeve and along the stem is permitted.

A further object of the invention is to provide a holder of the class described which is of simple structure and comprises a minimum number of parts.

The invention possesses other objects and features of advantage, some of which, with the foregoing, will be set forth in the following description of a preferred form of the invention and in the accompanying drawings in which,

Figure 1 is a side view of a holder embodying the invention, a cigarette being shown mounted therein.

Figure 2 is a side view of the holder but with the parts disposed as for the ejection of a cigarette butt, an operating hand and ejected cigarette butt being indicated in the view.

Figure 3 is an enlarged fragmentary axial section through the holder, the parts thereof being related as in Figure 1.

Figure 4 is an enlarged fragmentary side view of the holder with its parts related as in Figure 2 and the sleeve portion shown in axial section.

Figure 5 is an enlarged fragmentary view of a portion of the showing of Figure 4.

As particularly illustrated, the present invention is incorporated in the structure of a holder 6 comprising a cigarette holding sleeve 7 and a stem 8 having an end thereof telescopically engaged in the sleeve. A major and intermediate portion 9 of the sleeve bore is cylindrical for compressedly and frictionally receiving the butt end of a cigarette 11 part way therethrough and from the outer end thereof. To facilitate the mounting of

a cigarette in the sleeve, the bore portion 12 outwardly of the portion 9 is tapered whereby a funnel-like approach is provided to said last bore portion. An inner end portion 13 of the sleeve bore is of less diameter 55 than the bore portion 9 and is also cylindrical, while a conically tapered bore portion 14 is provided for connecting the bore portions 13 and 9. Preferably, and as shown, the sleeve bore portions 9, 12, 13 and 14 are 60 coaxial. The sleeve 7 is generally frustoconical in outline and is preferably formed to present an attractive appearance and to at the same time facilitate its manipulation with respect to the stem. As shown, an intermediate portion of this member is provided with a knurled outer surface, and a protruding ridge 15 is provided about it adjacent its inner end.

The stem member 8, it will now be noted, is 70 provided with a longitudinal passage 16 therethrough, and a cylindrical outer end portion 17 thereof is arranged to serve as an ejecting head for effecting a removal of a cigarette or cigarette butt from its mounted 75 position in the sleeve. The ejecting head 17, it will be noted, is arranged for reciprocation solely through the bore portions 9 and 12 and is preferably of somewhat less diameter than the bore portion 9 for a reason to be herein- 80 after brought out.

Immediately inwardly of the head 17, the stem 8 is enlarged to provide a circular and acute-angled edge 18 thereabout for a scraping engagement with the bore portion 9. 85 Preferably, and as shown, the edge 18 is provided at the intersection of a plane annular surface 19 extending from the base of the head 17 and perpendicular to the stem axis, with a conically tapered surface portion 21 of 90 the stem, whereby the scraping edge 18 is free with respect to the bore 9. The bore 9 is preferably provided with a finished surface whereby the edge 18 may function to remove 95 any deposits thereon when the sleeve and stem are axially displaced for ejecting a cigarette from the sleeve.

The inner edge of the stem surface portion 21 terminates in a cylindrical surface portion 22, which latter portion in turn terminates at 100

the outer edge of a conical surface portion 23 of the stem. The surface portion 23, it will now be particularly noted, is arranged for a tight and sealing engagement against the bore portion 14 and is therefore formed as complementary thereto whereby a seal may be provided when the faces contact. In order to insure a maximum width of contact between the sealing faces, the conical stem surface 21 is preferably made no wider than is necessary to insure a free scraping operation of the scraping edge 18 along the sleeve bore portion 9. The angle of obliquity of the contacting faces of the surface 23 and bore portion 14 is preferably slight and a ground fit is provided for these faces whereby they will be held frictionally locked together following their engagement.

The portion 24 of the stem immediately inwardly of the portion thereof providing the surface 23, and which is arranged for reciprocation through the inner bore portion 13, is cylindrical and preferably slidably engages said bore portion whereby an additional seal is provided between the stem and sleeve, said engagement of the sleeve and stem also serving to guide these members when they are moved relatively to each other.

It will now be noted that when the surface 23 and bore portion 14 are engaged, the holder is arranged to receive and retain a cigarette for the smoking thereof, such a relation of the parts being indicated in Figures 1 and 3. Under these conditions, the end face 25 of the head 17 is disposed to serve as a stop for limiting the degree of insertion of the cigarette within the bore portion 9, and a relative displacement of the sleeve and stem will thereafter cause an ejection movement of the cigarette outwardly through the bore portions 9 and 12 until the cigarette is no longer held and falls from the sleeve as shown in Figure 2. To limit such a relative displacement of the sleeve and stem to a degree just sufficient to accomplish the ejection, a stop is preferably provided on the stem, such stop in the present instance constituting a band 26 disposed in a shallow annular depression 27 therefore provided in the stem at an appropriate point thereof.

The formation of the ejecting head 17 to have a less diameter than that of the bore portion 9 through which it moves during an ejecting operation, it will now be noted, provides an annular space between it and the sleeve bore at all times. When the stem is moved to eject a cigarette, the scraping edge 18 is arranged to be moved only to the end of the bore portion 9. Under these circumstances, the bore 9 is completely cleaned during ejection of the cigarette and the scraped out material is in no way pressed against the bore portion 12, the latter having been found to occur if the larger stem portion of the scraping edge moves into the bore portion 12.

Any material on the surface of the bore portion 9 is thus but loosely adherent thereto, and a subsequent insertion of a cigarette in the holder when the sleeve and stem are in the relation shown in Figure 3, wipes such material from the bore portion 12 and within the sleeve cavity whereby it may be finally deposited in the space defined about the ejection head. In this manner, an ejection of a cigarette butt cleans the bore portion 9, while the insertion of a new cigarette cleans the bore portion 12, and the formation of deposits in the sleeve is positively prevented. The ejecting head 17, is of course, of such length as to insure the dropping of the butt on which it acts when the scraping edge 18 reaches its outer position in the sleeve.

The stem 8, it will now be noted, is preferably formed as a unitary member of hard-rubber, bone, amber, bakelite, or other suitable material. The sleeve 7 and stop ring 26 are preferably formed of metal or other suitable hard material which will take an attractive finish. In this manner, a minimum number of parts is required, it being noted that assembly of the holder would be accomplished by inserting the stem through the sleeve from the outer end thereof, and thereafter disposing the stop band in its place whereby a separation of the sleeve and stem is thereafter positively prevented.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. In a cigarette holder, a sleeve member having a cylindrical bore portion for receiving and retaining a cigarette, a stem member slidably and telescopically engaged in the bore of said sleeve member, and means on said stem member providing a scraping edge for engagement with and along the surface of said bore portion.

2. In a cigarette holder, a sleeve member having a cylindrical bore portion for receiving and retaining a cigarette, a stem member telescopically engaged in the bore of said sleeve member, means on said member providing a circular and radially outstanding scraping edge for engagement with the bore surface at said cylindrical portion thereof, and an ejecting head on said stem extending forwardly of the plane of said edge.

3. In a cigarette holder, a sleeve member providing an intermediate and cylindrical bore portion for receiving and retaining the butt end of a cigarette, a stem member tele-
- 5 scopically engaging the bore of said sleeve for ejecting a cigarette when the holder is contracted and being formed to provide a radially extending scraping edge for operative engagement along the surface of said
- 10 cylindrical bore portion during a contraction of the holder, and stop means on the members cooperative to prevent a disposal of said edge beyond the forward end of said bore portion when the holder is fully contracted.

15 In testimony whereof I affix my signature.

MILES F. DEACH.
